United States Patent Office.

WILLIAM G. CREAMER, OF BROOKLYN, NEW YORK.

Letters Patent No. 74,510, dated February 18, 1868.

IMPROVED SEAT-ARMS FOR RAILROAD-CHAIRS.

The Schedule referred to in these Letters Patent and making part of the same.

TO ALL WHOM IT MAY CONCERN:

Be it known that I, WILLIAM G. CREAMER, of Brooklyn, county of Kings, State of New York, have invented a new and improved Mode of Constructing and Attaching the Seat-Arms that hold the Backs of the Reversible Seats of Railroad-Cars; and I do hereby declare that the following is a full and exact description thereof, reference being had to the accompanying drawings, and to the letters of reference marked thereon.

The nature of my invention consists in the mode of attaching seat-arms to the seat-frames, and forming them in such a shape as to prevent the liability of breaking, by a more perfect system of annealing.

To enable others skilled in the arts to make and use my invention, I will proceed to describe its construction and operation.

Railroad-car seat-arms are now commonly made of malleable iron, so called, that is, cast of iron and then annealed. They are usually about five-sixteenths of an inch thick, and of the shape shown in the accompanying drawings, plates 1 and 2. It is a well-known fact in mechanics, that the process of annealing, as usually applied to what are termed malleable castings, seldom penetrates more than one-sixteenth of an inch from the surface; it is also well known that all kinds of malleable castings exceeding an eighth or three-sixteenths of an inch in thickness are comparatively brittle and unreliable, while thin, light castings are tough and ductile, and almost equal to wrought iron.

Malleable-iron seat-arms have always been made of the shape shown in the drawings, plates 1 and 2, and usually about five-sixteenths of an inch thick, and they have been found so liable to break that many companies have substituted brass and wrought iron, both of which cost more than double that of malleable iron.

My process of making seat-arms is to make them of the usual shape shown in the drawings, plates 1 and 2, and on one side, shown in plate 1, the arm is hollowed out, as shown in sections C D and E F. The opposite side and end of the arm that attaches to the seat-back are shown in plate 2, letters K L. Section G H, plate 2, is the obverse of section E F, plate 1.

This mode of construction, namely, making all parts of the arm thin, permits the annealing process to penetrate thoroughly; consequently the arm is as perfectly strong and reliable as if made of wrought iron or brass.

My method of attaching the arm to the side of the seat is also new, and is shown by plates 3 and 4. The usual way has been to rivet the pivot on which the arm revolves through the arm to a plate, and then screw on the plate to the seat-frame. Very often the rivet is not close up to the arm, or the rivet works loose, which makes a place to catch the fringe of ladies' shawls, or other parts of the garments, and this plan is also very troublesome in attaching the backs to the seat-frames, as the whole back has to be held while the plates are being screwed on-to the frame. My plan is to cast a pivot on the plate, shown at M, plates 3 and 4. At the end of the seat-arm, plate 1, section A B, is cast an opening, with a recess, N O. The plates, figs. 3 and 4, are then screwed on to the seat-frame, and the arms are screwed to the seat-backs, and then the arms are slipped over the pivots M M, at each end of the seat-frame, and a brass washer, P, plate 4, is let into the recess N O, and a screw, Q, is put through the centre of the pivot into the seat-frame. This plan of attachment, it will be seen, is much more perfect and simple than the ordinary way.

What I claim as my invention, and desire to secure by Letters Patent, is—

The construction of the pivot plate, with its nipple M and screw Q, in connection with the car-seat arm, the arm being either plain or recessed to receive the head of the screw or washer, all substantially as described and for the purposes set forth.
